UNITED STATES PATENT OFFICE

DEMPSON H. REED, OF HOUSTON, TEXAS

SETTING TOOL

Application filed May 14, 1931. Serial No. 537,339.

My invention relates to setting tools for use particularly in setting packers in wells.

One of the most effective types of packers employed in wells is collapsed longitudinally and thus forced to fill the space between the screen or liner and the interior of the casing by being forced downwardly by the use of the setting tool employed in lowering the strainer and packer into position. The principal difficulty with devices of this character heretofore has been that the arrangement for releasing the setting tool so that it may be used as a hammer in collapsing the packer has been unreliable. It has been necessary to rotate the setting tool to release it from engagement with the packer and in thus rotating the same the operation of the connecting means has been found to be unreliable in that it will not release when desired. It is an object of the invention to provide a setting tool to be used with packers for setting and expanding the same, which may be released without the necessity of rotation of the setting tool when the screen has been placed in position.

I desire to provide a positive latching engagement between the setting tool and the packer which will allow force to be exerted upon the packer when it is introduced into the well without danger of setting the packer prematurely.

I also have as an object to provide a setting device through which the circulation of liquid into the well may be carried out without influencing the latching engagement between the setting tool and the packer.

As a general object of the invention I desire to provide a setting tool which may be rigidly connected with the upper end of the packer and such engagement be assured throughout the setting of the device until the release thereof is desired.

In the drawing herewith, Fig. 1 is a central vertical section through a setting device constructed in accordance with my invention.

Fig. 2 is a transverse section on the plane 2-2 of Fig. 1.

Fig. 3 is a similar transverse section on the plane 3-3 of Fig. 1; and

Fig. 4 is a similar transverse section on the plane 4-4 of Fig. 1.

With reference particularly to Fig. 1, I have shown a pipe section 1, which may be understood as being a section of drill stem or other similar pipe to be used in setting a packer and the device connected therewith in a deep well for oil, gas, and the like. The lower end of the stem 1 is threaded at 2 for engagement within a threaded socket 3, at the upper end of a housing 4 for my setting device. Said housing is a cylindrical member having its interior formed to receive a mandrel 5. The lower end of the housing 4 is increased in internal diameter at 6, so as to engage over the radial flange 7 upon the lower section 8 of the mandrel.

The mandrel 5 is a tubular member fitting within the housing 4 and having a packing ring 9 thereon to form a fluid tight engagement with the interior of the said housing. Its lower end is connected at 10 with the lower extension 8 thereof. The interior of the mandrel is of uniform diameter throughout the greater portion of its length but is decreased in diameter toward the lower end to provide a shoulder 11, upon which a coil spring 12 may be seated. The interior chamber 13 within the mandrel provides a cylinder within which a piston 14 may fit. The said piston is a tubular block of material, the upper end of which has an annular plate 15 thereon, the outer periphery of which is provided with a packing ring 16 to engage within the cylinder chamber 13.

This plate 15 is connected to the head 14 of the piston by a plurality of cap screws 17. Said ring slopes inwardly and forms a seat within which a ball 18, shown in dotted lines in Fig. 1, may fit.

The sides of the body 14 of this piston are formed with a plurality of radial grooves 19 below the plate 15. These grooves are inclined inwardly from the lower end toward the upper end, the lower end being closed at 20. The said grooves are mortised or dovetailed, as shown at 21 in Fig. 4, to allow a sliding connection with latching dogs 22, which are provided with laterally extended tenons on the inner end to fit within the mor-

tised grooves and prevent the loss of said dogs from said slots. It will be noted that the downward movement of the piston head 14 relative to the dogs will have the effect of drawing the dogs inwardly in a radial direction. Said dogs project through openings 23 in the mandrel and through similar openings 24 in the outer housing 4 of the setting tool. When said dogs are in normal position at the lower end of said grooves 19 they project outwardly flush with the outer surface of the housing. Said dogs are tapered slightly outward so that they may be easily withdrawn when desired. As will be seen from Fig. 4, I have shown three such dogs working in slots in the side of the piston head 14.

As will be seen from Fig. 2, a longitudinal opening 25 is provided through the head 14 of the piston whereby a limited circulation of liquid therethrough may be accomplished at all times even when the ball 18 is in position closing the passage through the piston. The coil spring 12, seated on the lower end of the mandrel, supports the piston head 14 in position with the dogs 22 projecting through the housing, as shown in Fig. 1. The spring is under compression, however, tending to raise the piston when the dogs are released.

The lower extension 8 upon the mandrel is engaged at its lower end at 26 with the upper end 27 of the packer body or with a drill pipe extension as desired. The upper end of the member 27 has an extension 28, which is of large internal diameter but of smaller outer diameter than the said member 27. This extension forms the support for a packer. There is a gland member 29 connected with the outer upper end of the extension by means of a buttress thread, which allows the movement downwardly of the gland but prevents movement upwardly. Below the flange 30 at the upper end of the gland is a packing member 31, which may be of rubber or other compressible material, and which may be compressed outwardly against the wall of the casing in the usual manner.

Below the gland member 29, and within the compressible sleeve 31, is a ring or sleeve 32 of soft metal, such as lead, and it is to be understood that when the gland member 29 is forced downwardly it will compress the lead and force it outwardly beneath the sleeve 31 and assists in maintaining a fluid seal with the wall of the well.

To provide an indicating device to show when the setting tool has been properly operated, I provide a lateral opening 33 in the wall of the mandrel 5 above the piston. This opening, when the piston is in normal position, is above the piston and its outer end is closed against the inner wall by means of the packing ring 34. There is another opening 35 in the wall of the housing spaced somewhat above the opening 33, and it is to be understood that when the mandrel 5 is raised slight-

ly the openings 33 and 35 will register to allow an outlet of liquid from the housing.

There are a plurality of keys 36 on the housing extending inwardly and engaging within keyways 37 in the outer wall of the mandrel. These keys serve to hold the housing and mandrel nonrotatably together and when the mandrel is in normal inoperative position the keys 36 will be at the upper ends of the slots and will assist in supporting the mandrel.

In the operation of my device the parts are assembled as shown in Fig. 1 and introduced downwardly into the well. When the device has been placed in position with the extension 27 resting upon the bottom of the well, the well may then be washed. The liquid will be pumped downwardly through the passages indicated through the setting tool and when this has been accomplished, the packer may be set.

The setting of the packer is performed by dropping the ball 18 from the surface downwardly through the drill stem 1 and thus closing the opening through the piston 14. Water pressure may then be employed to exert a pressure downwardly upon the piston 14. The operator will then exert a slight thrust downward upon the drill stem to move the housing 4 downwardly to release the wedging effect between the housing and the mandrel and allow the piston to move downwardly sufficiently to withdraw the dogs 22 from the housing. The housing may then move downwardly relative to the mandrel and the opening 35 coming opposite the opening 33 will allow a release of pump pressure above the piston and indicate to the operator that the dogs 22 have been withdrawn and released. The further downward pressure upon the housing will bring the lower end thereof into contact with the gland upon the packer and force it downwardly to compress the same longitudinally and seat the same. A series of blows may be struck by the housing upon the packer to completely seal the space outside the packer and within the casing. When this has been done the device may be unscrewed from its connection 10 and withdrawn, leaving the packer in the hole. The connection at 10 may be a lefthand thread, if desired, so that the setting tool may be disconnected by righthand rotation.

This device may be positively operated by the simple use of pump pressure and it will be clear to the operator at all times as to the action of his tool. The operation is therefore simple and effective and is not liable to fail in use.

What I claim as new is:

1. A device of the character described including a stem, a housing sleeve thereon, a mandrel slidable in said housing, a packer on said mandrel below said housing, means connecting said mandrel to said housing, re-

leasable in response to fluid pressure, said housing when released being adapted to compress said packer.

2. A device of the character described including a stem, a housing sleeve thereon, a mandrel slideable in said housing, a packer on said mandrel below said housing, means connecting said mandrel to said housing releasable in response to fluid pressure, means operative on a slight relative downward movement of said housing to indicate that said releasable means has been withdrawn from said housing, said housing when released being adapted to compress said packer.

3. In a device of the character described, the combination including a stem, a tubular housing thereon, a mandrel telescoping within the lower end of said housing, a radially extending latching means connecting said mandrel and housing rigidly together, means engaging said latching means responsive to fluid pressure to withdraw said latch and release said housing.

4. In a device of the character described, the combination including a stem, a tubular housing thereon, a mandrel telescoping within the lower end of said housing, a radially extending latching means connecting said mandrel and housing rigidly together, means engaging said latching means responsive to fluid pressure to withdraw said latch and release said housing, and a packer below said housing adapted to be engaged and set by the relative downward movement of said housing.

5. In a device of the character described, the combination including a stem, a tubular housing thereon, a mandrel telescoping within the lower end of said housing, a radially extending latching means connecting said mandrel and housing rigidly together, means engaging said latching means responsive to fluid pressure to withdraw said latch and release said housing, and a packer below said housing adapted to be engaged and set by the relative downward movement of said housing, and means to prevent relative rotation of said mandrel and housing.

6. In a device of the character described a stem, a tubular housing thereon, a mandrel within said housing and projecting below said housing, a packer below said housing, means to prevent engagement of said housing with said packer to set said packer, said means being releasable by liquid pressure, and means to indicate that said housing has been released.

7. In a device of the character described, a stem, a tubular housing thereon, a mandrel within said housing and projecting below said housing, a packer below said housing, means including radially-extending latching dogs to prevent engagement of said housing with said packer, means on said housing to

set said packer, means having sliding engagement with said dogs, said means engaging said dogs being releasable by liquid pressure, and means to indicate that said housing has been released.

8. A drill stem, a housing thereon, a mandrel in said housing projecting below the same, a packer on said mandrel below said housing, latching dogs projecting through said housing and mandrel to hold them rigidly together, and a piston engaging said dogs, responsive to fluid pressure to move downwardly and withdraw said dogs from said housing whereby said housing may be moved downwardly to set said packer.

9. A drill stem, a housing thereon, a mandrel in said housing projecting below the same, a packer on said mandrel below said housing, latching dogs projecting through said housing and mandrel to hold them rigidly together, and a piston engaging said dogs, responsive to fluid pressure to move downwardly and withdraw said dogs from said housing whereby said housing may be moved downwardly to set said packer, said piston having a longitudinal fluid passage adapted to be closed by a ball valve.

10. A drill stem, a housing thereon, a mandrel in said housing projecting below the same, a packer on said mandrel below said housing, latching dogs projecting through said housing and mandrel to hold them rigidly together, and a piston engaging said dogs, responsive to fluid pressure to move downwardly and withdraw said dogs from said housing whereby said housing may be moved downwardly to set said packer, said mandrel and housing being releasable from said packer by rotation of said mandrel.

In testimony whereof I hereunto affix my signature this 5th day of May A. D. 1931.
